Nelson M. Howard

UNITED STATES PATENT OFFICE

AUGUST R. SCHOENKY, OF BEVERLY, MASSACHUSETTS, ASSIGNOR TO THE CELASTIC CORPORATION, OF WILMINGTON, DELAWARE, A CORPORATION OF DELAWARE

METHOD OF TREATING SHOE STIFFENER BLANKS

Application filed November 18, 1928. Serial No. 320,396.

This invention relates to a method of treating stiffener blanks for parts of boots and shoes and is herein described with particular reference to treating toe stiffener blanks.

5 In the manufacture of shoes, it is customary to employ a toe stiffener to aid in imparting the desired shape to the toe portion of the upper of the shoe and in maintaining this desired shape. In the case of plain-toed 10 shoes, which have no toe cap or tip, it is customary to use a so-called "soft box toe stiffener", that is, one without much stiffness or resilience. A stiffener for use in such shoes should have a comparatively soft rear margin 15 since otherwise a ridge or break will appear across the toe portion of the upper in register with the rear edge of the stiffener after the shoe has been subjected to a short period of wear. The whole upper portion of the 20 stiffener should also be comparatively soft, that is, it should have only just enough resilience to maintain the desired shape in the adjacent portion of the upper; but the front wall of the stiffener—or both the front and 25 side walls—should be comparatively stiff so as to furnish a firm foundation, so to speak, for the softer upper portion of the stiffener.

According to the method of the present invention, an absorbent stiffener blank is first 30 treated in a manner to reduce its absorptivity in the locality in which the finished stiffener should be soft, and is then treated with a liquid which is absorbed wholly or principally in the locality in which the finished stiffener should be comparatively hard.

The illustrated stiffener blank is of that 35 type which comprises a base of sheet material impregnated with a precipitated colloid, the colloid in its precipitated form imparting 40 very little stiffness to the blank. Such blanks are dipped in a solvent for the colloid, incorporated in the upper of a shoe, conformed to the toe portion of the last while wet and limp and allowed to stand until the 45 solvent evaporates, the colloid emerging from its solution in a horny or filmy form which is stiff and resilient. In accordance with the present invention, as herein exemplified, in order to prevent any considerable 50 amount of the solvent from being absorbed by

that portion of the blank which is to form the upper part of the stiffener in the finished shoe, that portion of the blank is compressed so as to reduce its absorptivity before the blank is treated with the solvent. Most of the colloid 55 in this portion, therefore, remains in its precipitated form in which it imparts very little stiffness to the stiffener while the remaining colloid is changed into its horny form to provide stiff front and side portions. 60

Referring to the accompanying drawings, Fig. 1 is a plan view of a stiffener blank after it has been compressed in the selected locality, and

Fig. 2 is a section on a greatly enlarged 65 scale on the line 2—2 of Fig. 1.

The illustrated stiffener blank is of the type disclosed in United States Letters Patent No. 1,256,240 granted February 12, 1918 upon an application filed in the name of 70 Stanley P. Lovell. Blanks of this type consist of a base of felt or woven fabric in which a colloidal substance, such, for example, as celluloid, has been precipitated. The blank in this state has comparatively little resilience. When, however, the blank is immersed in a solvent for the colloidal substance (for example alcohol, if the colloid is celluloid) and then allowed to stand until the solvent evaporates, the colloidal substance is changed 75 over to its horny or filmy form in which it is strong and resilient.

The blank in its original state has about the degree of resilience desired for the portion of the blank which, in the finished shoe, 80 should be comparatively soft. This portion, indicated at 3 and bounded by the rear edge 5 of the blank and a marginal zone 7 extending along the front and side edges of the blank, is therefore compressed. A more or less diagrammatic representation of what is 85 believed to result from the compression is indicated in Fig. 2. In the uncompressed portion 7 of the blank the particles 9 of the precipitated colloidal substance are more or less spaced from one another. At any rate the substance is porous so that it will readily absorb a solvent. In the compressed portion, on the other hand, the particles of the colloidal substance have been squeezed together to 90

100

such an extent that the absorptivity of the substance in that locality has been greatly reduced. Consequently, when the blank is dipped momentarily in a solvent, very little if any of the solvent is absorbed by the portion 3, but the portion 7 is almost instantly saturated. The blank is then incorporated in the upper of a shoe and conformed to the toe portion of the last during the pulling over and lasting operations; and, when the solvent has evaporated, there results in the finished shoe a box toe stiffener having a soft upper portion and a comparatively stiff and resilient front and side portion.

In order to promote brevity, the method has been described with reference to the compression of a portion of a blank and the subsequent treatment of the blank with a solvent liquid. It should be understood, however, that the method, in its broader aspects, is not limited to the use of compression to reduce absorptivity, to the particular sort of blank or to the particular sort of liquid which has been described.

Having thus described my invention, what I claim as new and desired to secure by Letters Patent of the United States is:

1. The method of treating an absorbent shoe stiffener blank which comprises reducing the absorptivity of the blank in a selected locality and then treating the blank with a liquid whereby the liquid is absorbed in different quantities per unit volume of the blank in different localities.

2. The method of treating an absorbent shoe stiffener blank which comprises compressing the blank in a selected locality and then treating the blank with a liquid whereby the liquid is absorbed in different quantities per unit volume of the blank in different localities.

3. The method of treating an absorbent box toe blank which comprises reducing the absorptivity of the blank in its middle and rear portions and then treating the blank with a liquid.

4. The method of treating an absorbent box toe blank which comprises compressing the blank in its middle and rear portions and then treating the blank with a liquid.

5. The method of treating an absorbent box toe blank which comprises reducing the absorptivity of the blank in a locality bounded by the rear edge of the blank and a zone extending along the margin at the front and sides of the blank and then subjecting the blank to the action of a liquid.

6. The method of treating an absorbent shoe stiffener blank containing a stiffening substance in a porous absorptive state which comprises reducing the absorptivity of the stiffening substance in a selected locality of the blank and then treating the blank with a liquid which tends to soften the stiffening substance.

7. The method of treating an absorbent shoe stiffener blank containing a stiffening substance in a porous absorptive state which comprises compressing the stiffening substance in a selected locality of the blank and then treating the blank with a liquid which tends to soften the stiffening substance.

8. The method of treating an absorptive shoe stiffener blank containing a precipitated colloidal stiffening substance which comprises compressing the blank in a selected locality and then treating the blank with a solvent for the colloidal substance.

9. A step-product consisting of an absorbent shoe stiffener blank, having a given density throughout a zone extending along a margin of the blank and having a greater density throughout the remaining portions of the blank.

In testimony whereof I have signed my name to this specification.

AUGUST R. SCHOENKY.
